UNITED STATES PATENT OFFICE.

ELMER SCHNEIDER AND JOHN GORMAN, OF CLEVELAND, OHIO.

TIMER.

Application filed January 6, 1923. Serial No. 611,027.

To all whom it may concern:

Be it known that we, ELMER SCHNEIDER and JOHN GORMAN, the former a citizen of the United States and the latter a citizen 5 of Canada, both residing at Cleveland, in the county of Cuyahoga and State of Ohio, have invented certain new and useful Improvements in Timers, of which the following is a specification.

10 This invention relates to timers for the ignition circuit of internal-combustion engines, and more particularly to the type having a rotor moved by the crank shaft of the engine for making and breaking the electric circuit of the spark plugs in successive order.

15 The main object of the invention is to provide a timer of simple and practical design constructed of a few parts which are readily assembled, and the parts subjected to the greatest wear easily replaced.

20 Another object of the invention is to provide a timer of said character which is steady and smooth in its action, reliable in 25 operation, and will wear well.

25 With the above and other objects in view, the invention will be hereinafter fully described as illustrated in the accompanying drawings, and the novel features thereof will 30 be distinctly pointed out in the appended 35 claim.

40 In the drawings similar characters of reference are used to designate corresponding parts.

45 Figure 1 is a longitudinal sectional view of a timer constructed in accordance with our invention.

Fig. 2 is a face view of same,

Fig. 3 is an end view of the arm with the 40 shoe pivoted thereto,

Fig. 4 is a similar view, the near lug of the arm and the near side of the shoe being broken away to better show the construction, and

50 Fig. 5 is a perspective view illustrating the shoe.

Referring to the drawings, 1 represents a cylindrical casing having a central hollow boss 2 which is provided at its closed end 55 with the usual depression 3 for receiving the spring for holding the casing in operative relation as will be understood. An operating arm 4 forms a part of said casing for adjusting the same in the well known man-

ner. Upon the inner face 5 of the casing is arranged a disk 6 of insulation material having an outer face 7, which is provided with a plurality of equally distant recesses indicated by 8. The disk 6 is provided with center openings 9 extending from the recesses 8 to the inner face of the disk, and in alignment therewith the casing 1 is provided with openings 10. Binding posts 11 pass through the openings 9 of the disk and the openings 10 of the casing, and their heads 12 fit into the recesses 8 of said disk and their outer ends are flush with the outer face 7 thereof. Washers of insulation material, indicated by 13, are arranged upon the binding posts 11, and nuts 14 thereon serve to hold said parts in position. Thumb nuts on said binding posts are adapted for attachment of the circuit wires thereto.

To the rotatably mounted timer shaft 15 is fixed a radially extending arm 16 carrying a pair of spaced transversely extending lugs 17 and 18, between which and to same is pivoted a shoe 19 by means of a bolt 20. The shoe 19 is supported to give a rocking action in the direction of the rotary movement of said arm, and is opened therethrough at 21 for receiving a collar or sleeve 22 which is mounted upon the bolt 20. A suitable coiled spring 23 is arranged upon said collar or sleeve, one end 24 of which engages the inner side of the arm 16 and the other end 25 passes through the opening 21 of the shoe and engages the under side of its forward end bar 26. The shoe has a rounding rear end 27, which is adapted to be resiliently held in contact with the outer face 7 of the disk 6 and the heads 12 of the binding posts 11 by the action of the coiled spring 23 for making and breaking the circuit as will be understood.

From the drawings and description, it will be readily seen that this timer is of practical construction, is convenient to assemble or replace worn parts, and that it is efficient because steady and smooth in action and reliable in operation. It will be understood that slight changes in the details of construction may be made within the scope of the claim.

Having fully described our invention, 105 what we claim is:

In a timer, the combination of a plurality of contacts arranged in a circle, a rotatable

arm, a shoe, the shoe being provided with a recess having sides and an end bar, a pivot pin passing through said sides of the shoe and connecting the shoe to said arm, a coiled 5 spring upon said pin within said recess and having free ends, and one of the ends of the spring engaging said end bar of the shoe

and the other end thereof engaging said arm for holding said shoe in engagement with said contacts, substantially as described. 10
In testimony whereof we affix our signatures.

ELMER SCHNEIDER.
JOHN GORMAN.
